CARL H. BISSELL, OF SYRACUSE, NEW YORK, ASSIGNOR TO CROUSE-HINDS COMPANY,
OF SYRACUSE, NEW YORK, A CORPORATION OF NEW YORK

RESYNCHRONIZING MEANS FOR TRAFFIC SIGNALING SYSTEMS

Application filed October 27, 1930. Serial No. 491,349.

- This invention relates to systems having master and secondary controllers as traffic signaling systems for highway intersections of the general type shown in my pending application Sr. No. 460,771, filed June 12, 1930, and has for its object a particularly simple and efficient control means for comparatively small systems, which control means synchronizes or resynchronizes the system periodically so that the signals of the system maintain a predetermined timing or order. The system of application Sr. No. 460,771 is primarily adapted for larger systems for cities and the present invention is intended for smaller systems of a comparatively small number of signals or, in other words, a system particularly adapted for villages where there are but two, three or four intersections to be guarded.
- The invention consists in the novel features and in the combinations and constructions hereinafter set forth and claimed.
- In describing this invention, reference is had to the accompanying drawing in which like characters designate corresponding parts in all the views.
- Figure 1 is a diagrammatic view illustrating the application of the system to a system of streets.
- Figure 2 is a schematic diagram of this traffic system.
- The particular construction of the motors, timers, switches, etc. form no part of this invention and constitute the subject matter of said application Sr. No. 460,771, and complete understanding of the present invention can be had more clearly without a detailed description of the motors, timers and other mechanical parts.
- This traffic signaling system comprises generally a master controller including an electric motor, a timer, and a secondary controller for controlling the signals at each intersection and each including an electric motor and timer, and means controlled partly by the master controller and partly by the secondary controller at each intersection for stopping the secondary controller at predetermined intervals preferably once during each traffic cycle.
- The signals are usually green lights for go and red lights for stop with or without an intermediate warning signal, usually an amber light. These signals pass through repeated traffic cycles from go to stop on one highway, stop to go on the intersecting highway and back to go on the first highway, go and stop on the intersecting highway. By traffic cycle period is meant the total time it requires for the signals to make one complete cycle. This may be a total period of say sixty, ninety, one hundred or one hundred and twenty seconds, etc. The traffic cycle period may be divided up evenly, that is, the traffic cycle period of one hundred seconds may be divided fifty seconds go on each street, or may be divided in any other manner as sixty seconds go on the main street and forty seconds go on the intersecting street with forty seconds stop on the main street and sixty seconds stop on the intersecting street.
- In the illustrated embodiment of my invention, the total traffic cycle depends upon the speed of the motor of the master controller.
- 1 designates the main street. 2, 3, 4 and 5 intersecting streets, there being signals located at each intersection controlled by controllers 10, 11, 12 and 13, the controller 10 which controls one intersection, serving as a master controller for the system and the controllers 11, 12 and 13 being secondary controllers. 14 designates generally the electric motor of the master controller, and 15 the timer shaft actuated by the motor, this timer shaft having cams not shown thereon for controlling the display of the signals. 16 designates the secondary motor at each intersection and 17 the timer shaft having cams thereon, not shown, for controlling the display of signals at that intersection. The timing cams may be of any suitable construction, but as the construction thereof forms no part of this invention, and as the construction and operation of timing cams are well known, and further as a full description thereof is unnecessary to completely understand the present invention, further description is thought to be unnecessary but for a full description

reference is had to the pending application referred to.

18 are the energizing or driving coils of the motor 14 of the master controller, these 6 being connected by wires 18^a and 18^b to the supply wires. 19 designates the energizing or driving coils of the motor 16 of each secondary controller, these being connected by wires 20 and 20^a to supply wires. The driving coils of all the motors may be connected to the same source of supply or may be connected independently of each other to the local feed wires. The secondary controllers are synchronized or resynchronized periodically, as once during each traffic cycle and are controlled in the synchronizing partly by the master controller and partly by the secondary controller at each intersection and the synchronization is effected by stopping or stalling 20 the secondary motors once during each traffic cycle. The secondary motors are preferably stalled by energizing normally idle bucking coils.

21 designates the bucking coils of each secondary motor, these, when energized, acting in opposition to the driving coils 19 and completely opposing the same. The flow of current to the bucking coils is controlled partly by the master controller and partly by each 25 secondary controller, that is, the companion secondary controller, and in the illustrated embodiment of this invention, the bucking coils of each secondary motor are connected in a circuit having a normally closed switch 30 therein operated by the master controller and a normally open switch therein operated by the companion secondary controller. The bucking coils are connected in the feed circuit through conductors 22 and 23, a normally 35 open switch designated generally 24 in the conductor 23, to be presently described, a change over switch 25, and a normally closed switch 26. The switch 25 forms no part of the invention. The switch 24 is closed once 40 during each traffic cycle by the companion secondary controller. The switch 26 which is normally closed, is opened once during each traffic cycle of the master controller. The switch 26 is operated by a cam 27 on 45 the timer shaft 15 of the master controller, this cam having a comparatively long, high or dwell portion which coacts with a movable switch arm 28 and normally holds the switch 50 26 in engagement with the contact 29. The cam is also formed with a low portion or depression 30 which when it comes opposite the arm 28 permits or causes the switch arm 26 to separate from the contact 29 and thus open the 55 bucking coil circuit. The switch 24 comprises spaced apart contacts 31, 32, an arm 33 for closing said contacts and a shifter or offset arm 34 movable with the shaft 17 of the secondary timer and operable to actuate the arm 33 against a returning spring 33^a to bring the

contacts 31 and 32 together once during each traffic cycle.

The master controller is set to run a little slower than the secondary controller, thus the offset arm 34 will operate the arm 33 to 70 close the bucking coil circuit before the switch arm 28 reaches the depression 30 of the cam 27. The traffic cycle period is determined by regulating the speed of the motors of the master and secondary controllers. These motors are usually of the induction disk type and the speed is controlled by adjusting the shading coils of the motor in the usual manner. During the operation of the system the offset arm 34 will actuate the arm 33 to engage 75 the contacts 31, 32 just prior to the time the recess 30 of the cam 27 comes opposite the switch arm 28, hence when the offset arm does engage and actuate the switch arm 33, the bucking coils 21 will be cut into a closed circuit so that the secondary motor 16 will 80 be stalled and all of the secondary motors will be stalled before the recess 30 comes opposite the switch arm 28. When the recess 30 does register with the switch arm 28, the 85 arm 26 will separate from the contact 29, thus opening the bucking coil circuits of each and all the secondary motors so that the secondary motors 16 will start and all of them will start at the same time. The timer shafts 17 90 will thus be actuated causing the offset arms 34 to ratchet past the switch arms 33 permitting said arms to return to their normal position and permit the contacts 31, 32 to separate so that the bucking coil circuits remain 95 open after the switch 26 is closed by the high portion of the cam 27 again operating the switch arm 28. The switch arm 33 of each secondary motor is returned by the suitable spring 33^a to its original position after it 100 is released from the offset arm 34. The contacts 31 or 32 or both are tensioned to move away from each other or one from the other, when the force holding them together is discontinued. The offset arms 34 of all the secondary controllers are timed to engage the 105 arms 33 before the low portion of the cam 27 of the master controller, registers with the follower of the switch arm 28.

The change over switch 25 forms no part 110 of this invention and it is merely for the purpose of connecting the bucking coils of some of the secondary motors in one synchronizing circuit and the bucking coils of others in another synchronizing circuit. The latter 115 circuit is controlled by a cam 270 for closing a normally closed switch 206 therein, the switches 24 of the bucking coil circuits may be connected selectively in circuit with the switch 206 by means of the switch 25. This switch 25 consists merely of a contact 36 arranged to coact with either one or the other of two contacts 37, 38. It is normally arranged to engage the contact 37, as shown in Figure 2, but if it is desired to connect the bucking 120 125 130

coils of any one or more secondary motors in circuit with the switch 206, then the switch arm 36 is shifted to engage the contact 38. It is shifted by means of a plug 39 insertable in a hole 40 against the arm 36 to press and hold it against the contact 38. There is one switch 25 for each secondary controller and this switch 25 is mounted adjacent a wall 41 of the casing of the secondary controller and the hole 40 is formed in said wall. This feature forms no part of this invention and is fully set forth in the pending application referred to.

What I claim is:

15 In a stop and go traffic signaling system for street intersections in which the signals pass through repeated traffic cycle periods, a master controller including an electric motor, a secondary controller for the signals at 20 each intersection including an electric motor, each motor having a driving coil, circuits for the driving coils which are constantly closed during the operation of the system, each secondary motor having a bucking coil, the electric motor or master controller being unprovided with a bucking coil, the bucking coil circuit having a normally closed and a normally open switch therein, means operated by the master controller for holding the normally closed switch closed and having means for opening the bucking coil circuit during each traffic cycle, each secondary timer having means for closing the companion normally open switch during each traffic cycle.

35 In testimony whereof, I have hereunto signed my name, at Syracuse, in the county of Onondaga, and State of New York, this 25th day of October, 1930.

CARL H. BISSELL.
